PROPELLER LOG

Paul Lövenörn Münster and Oscar Albin Thelin,
Horten, NorwayApplication November 18, 1931, Serial No. 575,944
In Germany June 2, 1931

4 Claims. (Cl. 73—122)

The invention relates to a propeller log for electrical transmission to an indicating apparatus on the bridge, in the chart-house or at any other suitable place on the ship.

- 5 According to the invention the propeller is arranged in a Pitot tube from which the driving water is conveyed to a discharge tube which encloses or is arranged alongside the Pitot tube and is closed at its upper end.
- 10 In order that the present invention may be the more readily understood reference is herein-after made to the accompanying drawing showing a constructional example of the present invention, Fig. 1 being a vertical section through 15 the log, Fig. 2 an upper end view of the log and Fig. 3 a detail. Fig. 4 shows a modified form of the lower end of the log, and Fig. 5 is an enlarged sectional view of a portion of the structure shown in Fig. 1.
- 20 Referring to the drawing, 1 is a Pitot's tube with inlet 2, and 3 is the propeller arranged in a wider part which forms the propeller box or casting 4 in the upper part of the Pitot tube. The water flows over the upper edge of the Pitot tube 25 to the discharge tube 5, arranged concentrically around the Pitot tube, and out through the outlet 6 opening to the rear.

The log is disposed in a tube 7 through which the log may be raised and lowered through the 30 bottom 8 of the ship, a sluice valve 9 being provided for closing the water way through the log. The tube 7 is provided with a stuffing box 10.

The position of the log in the tube 7 may be adjusted by changing the spacing pieces 11 interposed between flange 12 on the log and a corresponding flange 13 on the tube. As shown by the dotted lines in Figure 1, the upper ends of these spacers may be threaded in the flange 12 and of course turning the pieces will change 40 the distance between the two flanges, the spacers being retained in the position at which they are adjusted by means of set screws 11'.

The discharge tube is closed at its upper end by a removable cover 14 in which the shaft 15 of the propeller 3 is mounted in a sleeve 16 which may be filled with oil or fat to exclude moisture and for lubricating. The cover is shaped so as to avoid eddy-making and give smooth deflection of the water from the Pitot's tube to the discharge 50 tube. For instance the cover may be substantially conical or of toroidal shape so that the direction of flow of the water will be altered gradually.

The propeller shaft is at its upper end provided 55 with a worm 22 engaging a worm wheel 26 mount-

ed in a bracket 27 on the cover 14. Alongside of the bracket 27 is arranged an insulated plate 29 (Figure 5) holding a contact spring 30 which comes into contact with a contact pin or arm 28 on the wheel 26 for each revolution of the same. The pin 28 is in contact with the wheel and thereby grounded. To the contact spring 30 is by means of the contact screw 31 connected a cable 32 which leads to an indicating apparatus or a distance meter on the bridge or in another suitable place. In the line between the said contact screw 31 and the indicating apparatus is inserted a usual element from which the electromagnet in the counting device of the apparatus gets its voltage at each closing of the 15 circuit by the contact between the spring 30 and the contact pin 28 on the wheel 26. The indicating apparatus may, besides registering the distance covered and/or showing the speed, also be adapted to give a sound or light signal at each 20 closing of the circuit.

Owing to the contact device being arranged on the top of the apparatus and not in its submerged part, the error which often occurs in propeller logs owing to short circuitings caused by 25 the ingress of sea water is avoided.

For regulating the water stream and thereby the number of revolutions of the propeller, there is arranged in connection with the cover 14 a ring throttle 17 co-operating with corresponding 30 openings 18 in an extension of the Pitot's tube. The adjustment of the throttle is effected by turning the cover 14, to permit which the cover is not fastened by through bolts or screws, but is pressed against the upper edge of the discharge 35 tube 5 by means of the flange 19 and the pin screws 20. The flange 19 is provided with a scale 25 which in connection with a mark on the cover indicates the position of the valve throttle. The Pitot's tube is provided above the 40 said outlet openings 18 with a flange 21 by which it rests on the discharge tube and is secured against turning relatively to this tube by the pin screws 20.

If the log is to be used at much varying speeds of the vessel, irregularities in the water stream may arise at increasing speeds owing to the fact that the losses by impact and eddying of the water during its passage through the tube increase more than in proportion to the increase of speed. 45 In order to compensate for these irregularities, there may be arranged, preferably at the points where the water flows from the Pitot's tube to the discharge tube, automatic flap valves 24 as shown in Fig. 3, which valves at lower speeds of 50

the vessel serve to some degree to contract the water stream, but at increasing speed of the vessel, and consequently higher velocity of the water stream through the Pitot's tube, are opened automatically and thereby give a larger cross section of the passage for the water. Such flap valves may be arranged in front of one more of the said openings, suitably in front of one opening in the forward part and one in the afterpart of the tube.

10 Adjustment of the water stream also may be effected in a simple manner by lowering or raising the log in its guide in the ship's bottom so that the outlet 6 of the discharge tube is more or less covered thereby or is fully exposed. This may be obtained by adjusting or changing the above mentioned screws or distance pieces 11 between the flange 12 of the log and the flange 13 of the supporting tube 7.

15 In the constructional form of the lower end of the log as illustrated in Fig. 4, the tube enclosing the Pitot's tube is carried down approximately to the end of the Pitot's tube and both tubes are fastened to a casting in which the inlet to the 20 Pitot's tube is arranged and in which there are formed guides for the outlet of the water from the outer tube. This construction has the advantage that the outlet is located comparatively deep below the ship's bottom wherefore the effect 25 of the drag of the same upon the water is eliminated so that the correction curves of the log become more horizontal.

30 The arrangement of the propeller hanging from the cover of the propeller casing gives the advantage that the propeller may be easily removed for inspection when the log is pulled in and the valve 9 closed. At the same time the tube may easily be cleaned and freed from sea-weed or the like which may have entered the tube through the 35 forward inlet opening 2.

35 The widened propeller casing makes it possible to use a propeller of a comparatively large diameter working with a low number of revolutions whereby wear is reduced and a more solid construction made possible. The resistance of the transmission proper is reduced partly because the low number of revolutions of the propeller makes it possible to use fewer wheels for the driving of 40 the contact disc, and partly because the pressure of the teeth of the worm wheel against the worm on the propeller shaft and the dynamic pressure of the water both act in a direction opposed to the weight of the propeller whereby the friction

in the bearing of the propeller is reduced to a minimum.

What we claim is:

1. A ship's log, comprising in combination, a Pitot tube adapted to project through an aperture in the hull, a shaft coaxially disposed within the Pitot tube, a propeller mounted on said shaft, a discharge tube disposed concentrically about the Pitot tube, a cover for the discharge tube spaced from the inner end of the Pitot tube, and means disposed between the inner end of the Pitot tube and the cover for regulating the flow of water therebetween.

5 10 15 20 25 30 35 40 45 50

2. A ship's log, comprising in combination, a Pitot tube adapted to project through an aperture in the hull, a shaft coaxially disposed within the Pitot tube, a propeller mounted on said shaft, a discharge tube disposed concentrically about the Pitot tube, a cover for the discharge tube spaced from the inner end of the Pitot tube for deflecting the water from the Pitot tube into the discharge tube, and a ring valve located between the inner end of the Pitot tube and the cover for regulating the flow of water from the Pitot tube into the discharge tube.

3. A ship's log, comprising in combination, a Pitot tube adapted to project through an aperture in the hull, a shaft coaxially disposed within the Pitot tube, a propeller supported on said shaft adjacent the inner end of the tube, a discharge tube disposed concentrically about the Pitot tube, a cover for the discharge tube spaced from the inner end of the Pitot tube and formed to deflect the water from the Pitot tube into the discharge tube, and outwardly opening flap valves for regulating the size of the outlet from the Pitot tube into the discharge tube, said valves being located intermediate the inner end of the Pitot tube and the cover.

4. A ship's log, comprising in combination, a Pitot tube adapted to project through an aperture in the hull, a shaft coaxially disposed within the Pitot tube, a propeller supported on said shaft, a discharge tube disposed concentrically about the Pitot tube, a cover for the discharge tube spaced from the inner end of the Pitot tube and formed to deflect the water from the Pitot tube into the discharge tube, and means associated with said cover and disposed between the inner end of the Pitot tube and the cover for regulating the flow of water between said tubes.
